 Bendix Aviation Corporation, South Bend,
 Ind., a corporation of Delaware

Application July 12, 1939, Serial No. 283,939

19 Claims. (Cl. 123—169)

This invention relates to ignition apparatus for use in internal combustion engines and more particularly to spark plugs and methods for making the same.

It has been heretofore proposed to provide annular ground electrodes in spark plug bodies or shells and engage or secure them to the latter entirely around the inner periphery thereof by means of soldering, welding or the like. Although this manner of securing the electrodes in place has been quite satisfactory, difficulty has been experienced by way of having the same become loose and even drop out of the plug during use. Those which drop out into the engine cylinder often cause considerable damage to the cylinder and are apt to disable the engine. If an electrode becomes loose in its shell the conduction of heat therefrom to the shell of the plug and, hence, to the surrounding atmosphere is materially reduced, thereby permitting the electrode to become overheated to a point which may cause precombustion in the cylinder. Insofar as applicant is aware, no way has been ascertained for definitely determining whether or not an electrode has been soldered in place in a sufficiently secure manner to insure its remaining tightly in place during operation of an engine. It is not possible in each instance to determine whether or not the solder has flowed properly, for example, and whether or not it has become properly fused to the surfaces of the spark plug shell and the electrode.

Accordingly, one of the objects of the present invention is to provide a spark plug wherein the ground electrode is attached in the body or shell in a novel manner.

Another object of the invention is to provide novel means for securing annular ground electrodes in a spark plug body whereby it is substantially impossible for the electrode to drop out of the shell into the engine cylinder.

A further object is to provide a novel method for securing ground electrodes in spark plugs for use in internal combustion engines.

The above and further objects and novel features of the invention will more fully appear from the following detailed description when the same is read in connection with the accompanying drawing. It is to be expressly understood, however, that the drawing is for the purpose of illustration only and is not intended as a definition of the limits of the invention, reference being primarily had for this latter purpose to the appended claims.

In the drawing wherein like reference charac-

ters refer to like parts throughout the several views:

Fig. 1 is a side elevation, partly in section, of one form of spark plug embodying the present invention;

Fig. 2 is a bottom end view of the spark plug of Fig. 1;

Fig. 3 is a side elevation, partly in section and with parts broken away, of a second form of spark plug embodying the invention; and

Fig. 4 is a bottom end view of the spark plug illustrated in Fig. 3.

The forms of the invention shown in the drawing, by way of example, are illustrated as being embodied in radio shielded spark plugs, but it will be understood, of course, that the invention is applicable to any other type of spark plug whether shielded or unshielded.

In Fig. 1 the spark plug shown comprises a shell or body 10 which is adapted to be threadedly secured in an engine cylinder (not shown) in a manner well-known in the art and adapted to support a center electrode assembly comprising an electrode with an enlarged head portion 11 and a spindle 12, the latter of which is surrounded in the conventional manner by a tightly fitted copper sleeve 13. A mica sleeve or cigarette 14 surrounds sleeve 13 and tightly engages the walls of a bore through a nut 15 that threadedly engages shell 10. The upper ends of electrode spindle 12 and sleeves 13 and 14 project into a metallic shielding barrel 16 formed integrally with or otherwise secured to gland nut 15 and is adapted to be electrically connected to a source of high tension electrical current in a manner well understood in the art. Interposed between the lower end of gland nut 15 and head portion 11 of the electrode is a stack of mica washers 17 or other suitable insulating material.

Mounted in shell 10 in a novel manner for electrical cooperation with electrode 11, 12 is a ground electrode 18. In the form shown in Fig. 1 said ground electrode is cup-like in general outline with cylindrical wall 19 thereof slidably fitting into an enlarged bore 20 at the lower end of shell 10 and butting against an internal shoulder 21 in the latter that serves as a stop. For a purpose to hereinafter appear, the outer diameter of wall 19 is slightly less than the diameter of bore 20 and the internal diameter of said wall is substantially equal to the normal bore of shell 10. Projecting radially inward at a slightly downward angle from wall 19 are a plurality of prongs 22 which cooperate with electrode head 11 to form a spark gap.

The novel means for securing ground electrode 18, 19 in shell 10 comprises an annular groove 23 in the outer periphery of wall 19, said groove being preferably so positioned that the lower edge thereof, as viewed in Fig. 1, is substantially flush with or slightly below the lower edge of shell 10 when wall 19 butts against shoulder 21. At suitable intervals around the spark plug shell, portions 24 of the latter are staked or pressed into groove 23 for mechanically locking electrode 19 in place. As an additional holding means and for the purpose of providing good heat conduction from the ground electrode to the shell, silver solder or other suitable binding medium may be interposed between wall 19 and the inner wall of bore 20. Electrode 18 is thus doubly secured against removal or loosening.

In assembling shell 10 and ground electrode 18, the former is first counter-bored to form the enlarged bore 20 and shoulder 21. The shell is 20 then washed with a suitable solvent to remove all dirt particles and the walls of bore 20 are coated with a suitable soldering flux, such as borax, which may be in the form of a paste. The grooved electrode 18, which is preferably not provided at this stage with slots 25, is then placed in the shell and the assembled parts are subjected to a punching or staking operation in a die press equipped with tools for forming the tongues 24 that project into groove 23 and constitute the 30 mechanical holding means. In producing the embodiment of Figs. 1 and 2 a reciprocating punch with four equally spaced chisel-like prongs is employed.

Shell 10 is next supported by any suitable means in an inverted position and a ring of silver solder or other similar fusible material is positioned around the projecting portion of electrode 18. Additional flux adapted to promote the fusing of metals may now be placed on the solder ring and the entire assembly heated, preferably to a red heat, by any suitable means, such as an electrically heating coil surrounding the shell. The solder ring is thus melted and flows readily by gravity into groove 23 and the clearance space between adjacent surfaces of wall 19 and enlarged bore 20. The flux previously placed on these surfaces facilitates the flow of the molten solder and insures the fusing thereof with said surfaces. After the soldering operation, the shell and electrode assembly is pickled in acid to remove the scale therefrom and thereafter machined for the purpose of removing rough surfaces. Grooves 25 are then milled in electrode 18 to form prongs 22 and the entire assembly is polished for assembly with the center electrode assembly above described.

In the embodiment illustrated in Figs. 3 and 4, a modified center electrode 26 having a tapered or cone-shaped head portion 27 is shown. A copper tube 28 is combined with said electrode in a novel manner to facilitate heat flow from the electrode head, the upper surface of the latter being provided with an annular groove 29 into which a flanged portion 30 of the copper tube extends. The surface engagement between head 27 and tube 28, which has high heat conductivity, is thus materially increased, thereby increasing the rapidity of heat transfer from the electrode head to the tube.

Novelly secured in the lower end of shell 31 (Fig. 3) is a ground electrode 32 having a circular periphery engaging the walls of an enlarged bore 33 in the shell. The central portion of electrode 32 is cut away, as best seen in Fig. 4, and

portions thereof are bent downwardly to form prongs 34, the inner surfaces of which extend substantially parallel to the cone-shaped surfaces of electrode head 27. For the purpose of mechanically holding electrode 32 in shell 31, spaced portions 35 of the latter are pressed inwardly into overlapping engagement with the electrode, i. e., said portions are preferably staked into overlapping relation with the outer face of electrode 32 in the same manner that tongues 24 are staked against the inner shoulder of groove 23 in the embodiment of Fig. 1. Thereafter the electrode may be soldered to shell 31 in accordance with the novel method above-described in connection with the first embodiment. The solder is thus permitted to flow freely by gravity between the periphery of electrode 32 and the surface of bore 33 at the spaces between circumferentially spaced portions 35 which are pressed into engagement with the outer surface of the electrode. In the process of assembling and securing the parts in the manner illustrated in Figs. 3 and 4, the flux and solder are preferably applied in accordance with the novel method hereinabove described.

There is thus provided a spark plug wherein the ground electrode is secured in position in a novel manner to prevent loosening or loss thereof and to insure good heat conduction at all times between the electrode and the spark plug shell. A novel method is also provided for securing the ground electrode in a spark plug shell whereby said electrode is held in position both mechanically and by metallic fusion. Additionally, the invention provides a novel method for manufacturing reliable spark plugs in an inexpensive manner. A novelly constructed spark plug is also provided wherein heat conduction from the head of the center electrode is facilitated.

Although only two embodiments of the invention have been illustrated and described in detail, it is to be expressly understood that the same is not limited thereto. For example, various changes may be made in the design and arrangement of parts illustrated without departing from the spirit and scope of the invention as will now be apparent to those skilled in the art. For a definition of the limits of the invention, reference is had primarily to the appended claims.

What is claimed is:

1. A spark plug comprising an electrode assembly including a center electrode insulated from ground, a tubular shell for supporting said assembly in an engine cylinder, one end of said shell having an enlarged bore, a ground electrode mounted in said bore for forming a spark gap with said center electrode, spaced portions of said shell being staked inwardly into overlapping relation with portions of said ground electrode, and solder interposed between and fused to the adjacent surfaces of said shell and said ground electrode.

2. In a spark plug, the combination of a tubular shell having an enlarged bore at one end thereof, an electrode having a portion with a circular periphery positioned in said bore, only circumferentially spaced portions of said shell at said end extending inwardly into overlapping relation with parts of said electrode, and means interposed between and fused to the adjacent surfaces of said electrode and said shell.

3. In a spark plug, the combination of a tubular shell having an enlarged bore at one end thereof, an electrode having a portion with a circular periphery positioned in said bore, said por-

tion having an annular groove therein, circumferentially spaced portions of said shell extending into said groove, and means interposed between and fused to the adjacent surfaces of said electrode and shell, said last-named means filling said groove.

4. In a spark plug, the combination of a tubular shell having an enlarged bore at one end thereof forming an internal shoulder therein, an electrode engaging said shoulder and having a periphery conforming to said bore, only circumferentially spaced portions of said shell extending inwardly in a radial direction and engaging said electrode for holding the latter in position in said shell, and means interposed between and fused to adjacent surfaces of said electrode and shell.

5. In a spark plug, the combination of a tubular shell having an enlarged bore at one end thereof, an electrode having a periphery conforming to said bore and positioned therein, said electrode having an annular groove in the peripheral surface thereof, said groove having the outer edge thereof substantially flush with the end of said shell, circumferentially spaced portions of said shell extending into said groove and engaging said electrode, and fusible means substantially filling said groove and the clearance space between said shell and electrode for joining the same together.

6. In a spark plug, the combination of a tubular shell having an enlarged bore at one end thereof, an electrode having a portion with a circular periphery positioned in said bore, said portion having a circumferential groove therein, and circumferentially spaced portions of said shell extending into said groove and engaging said electrode for holding the latter in said shell.

7. In a spark plug, the combination of a tubular shell having an enlarged bore at one end thereof, an electrode having a circular periphery positioned in said bore, and circumferentially spaced portions of said shell staked inwardly to engage the outer surface of said electrode for holding the latter in the shell.

8. The method of making spark plugs which includes the steps of making a tubular shell having an enlarged bore at one end thereof, coating the wall of said bore with a soldering flux, positioning an electrode having a circular periphery with a circumferential groove in said bore, subjecting said shell to a punching operation to press circumferentially spaced portions thereof into said groove, supporting the assembled shell and electrode with the latter uppermost, placing a ring of fusible material thereon above the junction between said shell and electrode, placing a coating of soldering flux on said ring and adjacent portions of said shell and electrode, and heating said shell and electrode to melt said fusible material.

9. The method of manufacturing spark plugs which comprises the steps of making a tubular shell having an enlarged bore at one end thereof, coating the wall of said bore with a flux adapted to promote the fusion of metals, positioning an electrode having a circular periphery in said bore, subjecting said shell to a punching operation to press circumferentially spaced portions thereof inwardly into overlapping engagement with portions of said electrode, and causing a molten fusible material to flow into the clearance space between the adjacent surfaces of said shell and electrode.

10. The method of making spark plugs which

comprises the steps of making a tubular shell having an enlarged bore at one end thereof, coating the wall of said bore with a flux adapted to promote fusion of metals, positioning an electrode having a circular periphery and a circumferential peripheral groove in said bore, subjecting said shell to a punching operation to press circumferentially spaced portions thereof into said groove, and causing a molten fusible material to flow into said groove and into the clearance space between the adjacent surfaces of said shell and electrode.

11. The method of manufacturing spark plugs which includes making a tubular shell having an enlarged bore at one end thereof, positioning an electrode having a circular periphery in said bore, and subjecting said shell to a punching operation for simultaneously pressing circumferentially spaced portions thereof into overlapping relation with portions of said electrode.

12. The method of manufacturing spark plugs which includes making a tubular shell having an enlarged bore at one end thereof, placing an electrode having a circular periphery and circumferential groove therein in said bore, and subjecting said shell to a punching operation to simultaneously press circumferentially spaced portions thereof into said groove.

13. In a spark plug, an electrode assembly comprising a center electrode having a head portion and a stem portion, said head portion having an annular groove in the face thereof adjacent said stem portion, the inner periphery of said groove constituting a continuation of said stem portion, and a metallic tube having high heat conductivity surrounding said stem and having a flanged portion substantially filling said groove.

14. In a spark plug comprising an electrode assembly including a center electrode having a head portion and a stem portion, said head portion having an annular groove in the face thereof adjacent said stem, the inner periphery of said groove constituting a continuation of said stem, a metallic tube having high heat conductivity surrounding said stem and having a flanged portion substantially filling said groove.

15. In a spark plug, the combination of a tubular shell for supporting said assembly in an engine cylinder, one end of said shell having an enlarged bore, a ground electrode mounted in said bore for forming a spark gap with the head portion of said center electrode, spaced portions of said shell being pressed inwardly into overlapping relation with portions of said ground electrode, and fusible means interposed between and fused to the adjacent surfaces of said ground electrode and said shell.

16. In a spark plug, the combination of a tubular shell having a bore therein, an electrode having a portion with a circular periphery positioned in said bore at one end thereof, said portion having a circumferentially extending groove therein, and a portion of said shell at the end thereof staked into said groove and engaging said electrode for holding the latter in the shell.

17. In a spark plug, the combination of a tubular shell having an enlarged bore, at one end thereof forming an internal shoulder therein, an electrode engaging said shoulder and having a periphery conforming to said bore, and at least one portion of said shell being staked inwardly into overlapping relation with said electrode for holding the latter in position in said shell, the circumferential extent of said portion being less than the circumference of the shell.

17. The method of manufacturing spark plugs which includes making a tubular shell having an enlarged bore at one end thereof, positioning an electrode having a circular periphery in said bore, and staking the end of said shell by pressing a wedge-like tool into said end intermediate the inner and outer peripheries of the shell to press at least a portion thereof into overlapping relation with said electrode.

18. In a spark plug, the combination of a tubular shell having an enlarged bore at one end thereof, an electrode having a portion with a circular periphery positioned in said bore, said portion having a circumferentially extending recess therein, and means interposed between and

fused to adjacent surfaces of said electrode and shell, said means extending into said recess.

19. The method of manufacturing a spark plug which includes making a tubular shell having an enlarged bore at one end thereof, positioning an electrode having a circular periphery in said bore, and staking the end of said shell by pressing a wedge-like tool into said end intermediate the inner and outer peripheries of the shell to press at least a portion thereof of less circumferential extent than the circumference of said shell into overlapping relation with said electrode to mechanically lock the latter in said shell.
